UNITED STATES PATENT OFFICE.

ALBERT S. I. GABBS, OF SAN FRANCISCO, CALIFORNIA.

SOFA-BED AND LOUNGE.

SPECIFICATION forming part of Letters Patent No. 253,596, dated February 14, 1882.

Application filed March 22, 1880. (Model.)

To all whom it may concern:

Be it known that I, ALBERT S. I. GABBS, of the city and county of San Francisco, State of California, have invented a new, useful, and 5 Improved Sofa-Bed and Lounge; and I do hereby declare the following to be a full, perfect, and complete description of the same, reference being had to the accompanying drawings for illustration, in which—

10 Figure 1 is a longitudinal section of my improved sofa-bed and lounge, showing the head or pillow frame open and one section resting against the back-frame; and Fig. 2 is a cross-section thereof, showing the pillow or head frame in a like position.

15 This invention contemplates improvements in a combined sofa-bed and lounge; and it consists in combining with the seat-frame a pillow or head frame of two parts or sections 20 hinged together and adapted to be vertically adjusted, and a back-frame hinged to the seat-frame, and also adapted to be vertically adjusted or lowered to a horizontal position, as hereinafter more fully set forth.

25 In the accompanying drawings, A indicates the seat-frame, supported upon legs, as shown, while underneath and upon cleats of said frame slides a drawer, which, in addition to holding articles of apparel, may be slid out and caused 30 to support the back-frame when lowered to a horizontal position.

35 C' refer to the pillow or head frame, which is composed of two parts or sections, hinged together at one side to permit of the opening of the same and the enlargement of the frame. Furthermore, the hinging together of the parts of the pillow-frame allows one section to stand in an inclined or nearly perpendicular position and rest against the back-frame, as shown in 40 the drawings, to prop up the pillow at one side for the comfort of the occupant of the sofa or bed. The section C of the pillow-frame is itself hinged to the inner end of an upwardly-inclined extension of the seat-frame, upon which it is supported.

45 d, d' are ratchets, with their teeth or notches facing slots d' in the body of the ratchets, as seen in Fig. 1, and engaging staples d² in the inclined extension of the seat-frame. These 50 ratchets are pivoted to the section C of the pillow-frame, and are designed, in connection

with the staples d², to permit of the vertical adjustment of the pillow-frame, in order to raise or lower the head of the occupant, as may be desired. The slots d' of the ratchets, while 55 they permit the sliding of the ratchets upon the staples d², serve also to confine them in position upon the staples.

e is a cord or chain, with its ends attached to the ratchets, after having been passed through 60 eyes e' on the pillow-frame, while at its middle it is passed through a passage in the outer end of section C of the pillow-frame, as seen in Figs. 1 and 2, and thence provided with a ring or knot, e², as seen in Fig. 1. By pulling on ring or knot e² 65 the teeth of the ratchets are disengaged from their retaining-staples, which will allow the lowering of the pillow-frame. Simply the elevating of the outer end of the pillow-frame by the hand allows it to be adjusted and held at the desired height, the ratchets being so arranged or disposed with relation to their engaging-staples as to effect their engagement by gravity, as seen in Fig. 1.

70 B is the back-frame, connected by jointed plates or hinges b to the seat-frame A, and provided with the pivoted ratchets F, identical in construction with the ratchets d, and fitting in slots, (shown in dotted lines in Fig. 2,) in rearward extensions of the cleats upon which the 80 drawer L slides, and engaging with pins K, extending transversely through the aforesaid slots, as also seen in dotted lines in the same figure. The teeth of the ratchets F (as with those marked d) are disengaged from their 85 holding-pins K by pulling upon cords or chains J, connected to or extending from the ratchets F through the lower horizontal bar and upper short similarly-disposed bars, n, of the back-frame B. They are provided with rings or 90 knotted at their free ends for convenience in manipulating them. By this arrangement the back-frame B can be adjusted to stand at the desired angle of inclination to suit the comfort of the occupant, or it can be lowered to a horizontal position to convert the sofa into a bedstead and to enlarge the capacity thereof for comfortable reclining purposes. The back-frame, when adjusted to the latter mentioned position, is provided with a pillow or head-rest 95 by opening the frame C C', so as to bring its section C' about in line with the vertical lon-

5 gitudinal plane of the lower back-frame. The adjustment of the back-frame to its normal or elevated position is effected in the same manner as that pursued in the similar adjustment of the pillow-frame upon or with relation to the inclined extension of the frame A.

Having thus fully described my invention, I claim and desire to secure by Letters Patent—

1. The ratchet F, provided with an outer guard facing the row of notches, and having an enlarged notch or stop at the bottom, in combination with the pin K and the back B, substantially as set forth.

2. The combination of the stay-rod J, ratch-

ets F, and clips under the back B, for attaching the ratchets with the stays b, substantially as set forth. 15

3. The combination of the back B, supporting and adjusting means, and drawer capable of being drawn out and forming a support for the back when down in a horizontal position, as set forth. 20

In witness whereof I have hereunto set my
hand this 12th day of October, A. D. 1878.

ALBERT S. I. GABBS.
